UNITED STATES PATENT OFFICE

157,639

COMBINED COMPACT, CHANGE PURSE, AND LIPSTICK HOLDER

William S. Shea, New Rochelle, N. Y., assignor to Rex Products Corporation, a corporation of
New York

Application June 25, 1949, Serial No. 3,554

Term of patent 3½ years

(Cl. D86—10)

To all whom it may concern:

Be it known that I, William S. Shea, a citizen of the United States of America, residing in New Rochelle, county of Westchester, and State of New York, have invented a new, original, and ornamental Design for a Combined Compact, Change Purse, and Lipstick Holder, of which the following is a specification, reference being had to the accompanying drawing, forming part thereof, wherein,

I claim:

The ornamental design for a combined compact, change purse, and lipstick holder, substantially as shown.

WILLIAM S. SHEA.
